UNITED STATES PATENT OFFICE.

FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY.

THREAD-FASTENING MACHINE.

1,404,775.

Specification of Letters Patent. Patented Jan. 31, 1922.

Application filed December 20, 1919. Serial No. 346,399.

To all whom it may concern:

Be it known that I, FRED N. LA CHAPELLE, a citizen of the United States, residing at Beverly, in the county of Essex and

5 State of Massachusetts, have invented certain new and useful Improvements in Thread-Fastening Machines; and I do hereby declare the following to be a full, clear, and exact description of the invention, such 10 as will enable others skilled in the art to which it appertains to make and use the same.

The present invention relates to thread handling machines and more particularly 15 to machines of this type employed for temporarily securing the upper and insole lip of a lasted shoe prior to the inseam sewing operation.

In the machine disclosed in the patent to 20 La Chapelle No. 1,185,108, May 30, 1916, a single stitch or thread fastening is passed through the upper and insole lip of a lasted shoe to permit the removal of the lasting tacks from the shoe prior to the inseam 25 sewing operation. At the completion of this stitch the machine automatically cuts the thread and releases the shoe to permit the feeding of the latter to a new position. With this construction it is possible for an 30 operator to manipulate the shoe in such a manner that the thread fastenings are inserted between adjacent tacks, although the necessity for avoiding these tacks tends to retard somewhat the insertion of the thread 35 fasteners. Accordingly, in order to permit a rapid manipulation of the shoe it is desirable to provide some means for removing the lasting tacks should the shoe be positioned with a lasting tack located in the 40 path of the needle.

One object of the present invention, therefore, is to provide in a machine of this type mechanism for removing from the path of the needle any tacks which may be located 45 in line therewith or immediately adjacent thereto prior to the insertion of the thread fastening.

With this object in view a feature of the invention contemplates the provision in a 50 thread fastening machine provided with a sole support and co-operating back gage adapted to retain the shoe in position dur-

ing the operation of the stitch forming mechanism, of means for actuating the back gage during each cycle of operations of the 55 stitch forming mechanism in a manner to cause the upper edge of the gage to remove any tack which is located in its path.

In the simplest and most efficient form of the invention which has yet been devised the 60 back gage is moved inwardly and upwardly into operative relation with the channel guide to cause the removal of the lasting 65 tack prior to the advancing movement of the needle and is thereafter retained in operative position during the formation of the stitch.

Still further features of the invention consist in certain novel features of construction, combinations and arrangements of 70 parts hereinafter described and claimed, the advantages of which will be obvious to those skilled in the art from the following description.

In the accompanying drawings illustrating the preferred form of the invention, Figure 1 represents a side elevation of a thread fastening machine embodying the features of the invention; Fig. 2 is a detail illustrating the back gage and operating 75 mechanism prior to the engagement and removal of the tack; Fig. 3 is a detail illustrating the back gage after the tack has 80 been removed and in the position in which it is maintained during the insertion of the 85 thread fastening; Fig. 4 is a detail illustrating a plan view of the back gage and operating mechanism; and Fig. 5 is a detail 90 illustrating the combined back gage and tack puller upon an enlarged scale.

The machine shown in the illustrated embodiment of the invention is provided with 95 stitch forming mechanism and means for supporting the shoe during the insertion of the thread fastener, comprising a channel guide and a back gage which is moved toward and from the channel guide during each cycle of operations of the machine to hold the shoe in position during the insertion of the thread fastener and to release 100 and permit the feed of the shoe at the completion of the thread fastening. The stitch forming mechanism, as shown in the La Chapelle patent above referred to, passes

two loops of thread through the work from one side and interlocks these two loops of thread upon the opposite side of the work. During the formation of the thread fastening the shoe is held stationary and the needle is jogged laterally to space the loops. It sometimes happens that the operator positions the shoe with a lasting tack located in the path of the needle which interferes with the insertion of the thread fastening and may damage or break the needle. Furthermore the care which must be observed by the operator in order to avoid the tacks in all cases necessarily retards the manipulation of the shoe by the operator and in consequence lengthens appreciably the time required to complete each shoe.

According to the present invention the movement of the back gage toward and from the channel guide during each cycle of operations of the machine is utilized to remove any tacks which may be located in the path of the needle or immediately adjacent thereto. At the commencement of the cycle of operations the back gage first moves from the inoperative position in which it is located when the machine is at rest downwardly and inwardly toward the shoe and thence upwardly along the upper until it assumes approximately the position shown in Fig. 3 of the drawings in which the tack has been removed. During the operation of the stitch forming instrumentalities the back gage remains in this position and at the completion of the thread fastening operation the back gage is retracted to release the shoe and permit it to be fed to a new position.

The thread fastening machine comprises a stationary channel guide or sole support 10 and a co-operating back gage 12 provided with a slot 14 through which a curved needle 15 passes during the formation of the stitch. The back gage is supported upon the outer end of a carrier 16 movable between guides 17 and 18 in a direction to impart the proper movements to the back gage. The gage carrier 16 is connected at its rear end to a lever 20 fulcrumed upon the rock shaft 21 and oscillated from a path cam 23 which receives a cam roll 24 journaled upon the upper end of the lever, as shown clearly in Fig. 1. The forward end of the back gage carrier is pivotally and slidably supported upon one arm of a bell crank lever 25 fulcrumed upon the guide block 17 at 26 and having its opposite arm connected to an actuating lever 28 through a link 29. The lever 28 is oscillated to raise and lower the forward end of the carrier by a cam path 30 which receives a cam roll 32 journaled upon the end of the lever. As shown clearly in Fig. 4, this lever 28 comprises essentially two arms 33 and 34 which are pinned to the rock shaft 21. The shape of

the cam paths 23 and 30 is such that the back gage is caused to move in substantially the path shown in Fig. 1, first moving downwardly and inwardly toward the shoe, and then moving upwardly and inwardly to engage and remove a tack from the shoe, this movement all taking place prior to the first advancing movement of the needle. During the formation and insertion of the thread fastening the back gage is held stationary in substantially the position shown in Fig. 3 and is thereafter withdrawn at the completion of the thread fastening to the retracted position shown in Fig. 1. The combined back gage and tack puller is positively moved through the cycle of operations and in order to accommodate varying thicknesses of between-substance and ensure a sufficient spacing between the back gage and channel guide for the proper reception of the work, the back gage operating mechanism is ordinarily adjusted to cause the latter to assume a position during the insertion of the thread fastening in which the space between the back gage and channel guide is slightly greater than the thickness of the work. The operative position of the back gage may be readily varied through the provision of a threaded stem 35 projecting from the rear end of the carrier 16 and having lock nuts 36 and 37 which are disposed upon opposite sides of a sleeve 39 pivotally connected to the lower end of the lever 20.

It will be observed from an inspection of the drawings, more especially Figs. 4 and 5, that during the formation of the thread fastening the needle 15 passes through the slot 14 in the back gage at two separated points to carry the loops of thread through the work. With the present construction a tack which may be located between the two paths of the needle is removed, or if located in one of the paths or immediately outside, it is either removed or deflected so that it does not interfere with the needle. To this end the upper end of the back gage consists of a pair of wedges having apices located substantially in the paths of the movement of the needle, as shown clearly in Fig. 5. A tack which may be located between the apices is engaged and removed during the advancing movement of the tack puller and a tack which is located outside of either apex is engaged by the outer inclined face of the wedge and removed, or in any case sufficiently deflected so that it does not interfere with the proper movements of the needle.

While it is preferred to employ the specific construction and arrangement of parts shown and described, it will be understood that this construction and arrangement is not essential except so far as specified in the claims, and may be changed or modified

without departing from the broader features of the invention.

The invention having been described what is claimed is:

- 5 1. A thread handling machine comprising a stitch forming mechanism including a needle, a sole support and a cooperating back gage adapted to retain the shoe in position during the operation of the stitch forming mechanism, the back gage having a tack pulling edge, and means for actuating the back gage during each cycle of operations of the stitch forming mechanism to advance the back gage upwardly in a direction to cause the edge to engage beneath the head of a tack located in its path.
- 10 2. A thread handling machine comprising a sole support, a cooperating back gage having a tack pulling edge, and mechanism for actuating the back gage to engage beneath the head and remove a tack located in the path of the gage.
- 15 3. A thread handling machine comprising a sole support, a co-operating back gage having an upper edge adapted to engage a tack, and mechanism for moving the back gage inwardly and upwardly across the shoe to cause the gage to engage beneath the head and remove a tack located in its path.
- 20 4. A thread handling machine comprising a stitch forming mechanism including a needle, a channel guide and a cooperating back gage for positioning the shoe, the back gage having a tack engaging and pulling edge, and mechanism for moving the back gage inwardly and upwardly toward the shoe in a manner to cause the edge to engage and remove a tack from the shoe prior to the advancing movement of the needle.
- 25 5. A thread handling machine comprising a carrier, a back gage secured to the front end of the carrier and having an upper tack pulling edge, a lever connected to the rear end of the carrier and adapted to move the latter in a lengthwise direction, a second lever connected to the front end of the carrier and adapted to raise and lower the front end of the carrier, and mechanism for operating the two levers in timed relation to one another to impart a movement to the back gage designed to cause the upper edge to engage with and remove a tack from the shoe.
- 30 6. A thread handling machine comprising a channel guide, a co-operating back gage having a transverse slot formed therein and an upper end adapted to engage and pull a tack, a needle adapted to pass through the slot in the back gage, and mechanism for first depressing the back gage and for thereafter elevating and moving the back gage inwardly to impart a tack pulling movement to the gage prior to the passage of the needle therethrough.

FRED N. LA CHAPELLE.
